T. J. SULLIVAN, OF ROCHESTER, NEW YORK.

Letters Patent No. 67,927, dated August 20, 1867.

IMPROVEMENT IN PERMUTATION LOCKS FOR DOORS, &c.

The Schedule referred to in these Letters Patent and making part of the same.

TO ALL WHOM IT MAY CONCERN:

Be it known that I, T. J. SULLIVAN, of Rochester, in the county of Monroe, and State of New York, have invented a new and useful Improvement in Locks; and I do hereby declare that the following is a full and exact description thereof, reference being had to the accompanying drawings, making part of this specification.

Figure 1 is an elevation of the lock proper, with the back plate removed to show the interior arrangement, and with the bolt protruded.

Figure 2, a perspective view of the operating parts of the lock proper removed from the case.

Figure 3, an elevation of the cam-disk, a portion of the connecting-lever, the dog-plate, and the sliding-catch, as combined in action.

Figure 4, a section of the combination-wheels, and the segment-frame and stud that support them.

Figure 5, a perspective view of the parts constituting the fastening for the knob or key-shaft, the said parts being shown separated.

Figure 6, an elevation of that portion of the lock outside the lock proper for disconnecting the bolt-work of the safe-door from the operating parts when locked.

Figure 7, perspective view of the same arrangement.

Figure 8, perspective view of one of the combination-wheels.

Like letters of reference indicate corresponding parts in all the figures.

My improved lock belongs to that class known as combination locks for bank and safe use. The invention consists in an improved construction and arrangement of the working parts of the lock proper, and also of an improved connection of the heavy bolt-work of the safe-door with said lock proper, whereby the bolt-work may be detached or disconnected from the shaft that operates it from the outside so that no strain can be brought to bear upon it, but it is perfectly insulated and removed from reach.

As represented in the drawings, A is the case of the lock proper that is placed upon the door to be guarded. Through this passes the ordinary knob or key-shaft B, which is operated by a knob on the outside of the door. This shaft is held in place by screwing into a head, C, on the inside of the lock. Said head has nicks or indentations, b b, (fig. 5,) in which fit projections c c of a collar, D. A corresponding projection, c', of the collar fits into a longitudinal slot, a, of the knob-shaft. When this is done a jam-nut, E, screws up against the two parts and holds them firmly in contact, and they cannot become separated nor can the shaft unscrew. In this manner I secure the shaft so that it cannot be withdrawn, and at the same time I render it adjustable to doors of different thicknesses; for, by removing the jam-nut and collar at any time, it will be seen I can turn the screw to any desired position. This connection secures greater strength than in any other device for a similar purpose with which I am acquainted. The combination-wheels F F F, instead of resting upon the knob-shaft as an axis or bearing, as in some locks, or upon a projecting stud of the back plate, as in some other locks, rest upon a hollow bearing, d, (fig. 4,) of a frame, G, in the form of a segment, which is secured just inside the back plate by screws to studs f f f of the lock. By this arrangement the end of the knob-shaft does not extend through the wheels as usual, but simply comes opposite the bearings d, and the head C operates the wheels. While I thus avoid running the knob-shaft through as the bearing of the wheels, (in which case the wheels cannot be easily removed from place,) and avoid projecting a stud from the back plate of the lock to form a bearing for the wheels, (in which case the wheels must always be removed from place when the back plate is removed,) the employment of the segment-frame G enables me to either retain or remove the wheels easily, independent of either the shaft or back plate. This is of much advantage. The great result I accomplish, however, is that the action of the wheels is reversed from that of ordinary locks of this class, and therefore I can pick up the combination more readily; that is to say, the wheel next the back plate is first set, and then the others in succession, till all are set to the pre-arranged combination; therefore, if I desire to pick up or arrange the combination, all I have to do is to insert the usual key g through the hole h, (fig. 2,) in the segment G, and then necessarily through the corresponding holes in the wheels till they are all in order. In ordinary locks, since the wheel on the opposite side from the above is the one to be set first, this picking up of the combination is a work of some difficulty. On the shaft B, back of the head C, is situated a cam-disk, J, with three cams i k l, and a pin, m, having the relative positions indicated in fig. 3. Above the cam-disk rests the head of a lever, H, extending forward and connecting with the usual lock-bolt I by means of a bearing, n, striking into a socket

in its upper edge, or in some equivalent manner. The end next the bolt has a guide-slot, σ , resting over a guide-screw, p , to hold it in place and allow the necessary longitudinal movement. The end over the cam-disk has a similar slot, σ , but this slot passes over the usual dog q , striking into the notches of the combination-wheels. This dog is secured to a vertically acting plate, K , in the rear of the lever, having a guide-slot, σ , passing over a screw, r , for holding it in place. The lower edge of the head of the lever has a notch, s . Below the connecting-lever, and at one side of the cam-disk, is situated a slide, L , pressed forward by a spring, t . The end next the cam-disk is provided with a cam-head, u , and also with a rib or projection, v , which strikes into a corresponding depression or socket, w , of the dog-plate when the latter is raised, as shown in figs. 2 and 3. This slide is held in place by slots and screws similar to σ , p , &c., of the other parts. When the combination-wheels are being set the dog q rides in such a manner upon the end of the disk J as to touch the edges of the wheels but once, and then slightly, at each revolution of the shaft. When the notches of the wheels are all in coincidence with the dog a slight backward movement of the dog will allow the notch s of the lever to fall over the pin m , which forms such a connection that a reverse movement of the shaft will retract the lock-bolt. The relative arrangement of the cams i k l with the other parts is such as to allow the necessary stroke of the lever to throw the bolt, but to raise the lever at the proper times to disengage the parts and to throw the slide L out from engagement with the dog-plate K to allow the dog-plate to rise. It will be noticed that the cams i k serve simply to raise the lever, and the cam l to disengage the slide. Any person skilled in the art can produce the relative arrangement of these parts to act at the proper time and in the proper manner.

This arrangement of the parts, as above described, is simple and effective. The lever H is connected directly to the dog-plate K by the dog itself, an arrangement which I believe to be original with myself. The connection of the slide L with the dog-plate I also believe to be new. The combination-wheels in ordinary locks are made up of a rim and a centre, the latter being encased by the former, and secured by suitable means which will allow adjustment. I make my wheels, as shown in fig. 8, of simply a rim or disk, M , and a centre, N , the latter not being encased or enclosed, but simply having a bearing or hub resting in a socket of the rim. By this arrangement I not only avoid much extra labor, but also make the device much more effectual. Various devices have also been employed for holding the centre in position. In one, two grippers are used, with a spring to each, which strike against the smooth periphery of the encased centre. I corrugate or notch the projecting edge of my centre, as shown, and use two pawls or dogs x x pivoted to the side of the rim, and held in engagement with the centre by a single spring, y , secured to a stud, z , as shown, and bearing on both pawls. This simplifies the arrangement, and reduces the expense, and lessens the danger of displacement. The pawls are expanded to allow the combination to be changed by the key g passing through a hole in the wheel between them. On bank-safe doors the bolt of the lock is made to project against the stem a' of the heavy bolt-work O that shoots into the casing of the safe to secure it. In ordinary safes this bolt-work is operated by a separate shaft, B' , passing outward through the door, and having a knob or crank outside to slide it forward or back, as the lock will allow, since the bolt-work is too heavy to be thrown by the bolt of the lock. By applying great power to this shaft it is frequently the case that it will drive the bolt of the lock proper back, or at least disarrange the mechanism of the lock so that it cannot be unlocked. It also serves as a means to ascertain the combination on which the lock is set by its contact with the mechanism of the lock.

To obviate this difficulty I detach, disconnect, or isolate the bolt-work from its operating shaft when locked, and also make the connection of the bolt-work with said shaft by a separate combination of wheels, which must be set on the pre-arranged formula before the connection can be made. To accomplish this, I prefer the arrangement of parts as shown in the drawings. A set of combination-wheels, $F' F' F'$, are arranged upon the shaft B' , similar to those of the lock proper, with which engages a dog, q' , whose lever H' is connected with the bolt-work. When the dog engages with the wheels the bolt-work can be thrown forward or backward, but when it is thrown up, the bolt-work is disengaged. In order to thus throw up the dog-lever, I pivot at b' a bent arm, P , having at one end a pin, f' , that rests against the end of the lock-bolt, and at the other a pin, g' , that rests under the dog-lever. Thus, when the bolt is thrown forward the lever is thrown up, and *vice versa*. In order to hold the dog in place in the notches of the wheels in going back and forth, I employ a segment, Q , covering the edges of the wheels at the proper positions, as shown.

What I claim as my invention, and desire to secure by Letters Patent, is—

1. Connecting the shaft B with the head C by the collar D and jam-nut E , as herein set forth.
  2. Connecting the combination-wheels to the frame G , which is secured within the lock in the manner set forth, so as to avoid extending the shaft through it, or removing them with the back plate, as specified.
  3. Combining the lever H with the dog-plate K by the dog q , in such a manner that while they are bound together each is allowed a free action, as set forth.
  4. The combination of the slide L with the dog-plate K and lever H , as and for the purpose specified.
  5. The combination of the cam-disk J with the lever H , slide L , and dog-plate K , as specified.
  6. Disconnecting the heavy bolt-work of a safe-door from its operating-shaft when the door is locked, as specified.
  7. The combination of the bent arm P with the lever H' and the bolt of the lock, for the purpose set forth.
  8. The segment Q , in combination with the dog q' , and wheels $F' F' F'$, as and for the purpose set forth.
- In witness whereof I have hereunto signed my name in the presence of two subscribing witnesses.
